UNITED STATES PATENT OFFICE

JOHN M. LYONS, OF CHICAGO, ILLINOIS

PORTABLE CONFESSIONAL

Application filed August 8, 1928. Serial No. 298,346.

The present invention relates to a confessional and has for its prime object to provide a structure which may be folded in a compact manner and which may be easily and 5 readily attached to the back of a chair or the like in an extended manner. Thus the confessional is easily portable.

A still further very important object of the invention resides in the provision of a 10 confessional of this nature which is exceedingly simple in construction, inexpensive to manufacture, light, thoroughly efficient and reliable, and otherwise well adapted to the purpose for which it is designed.

15 With the above and numerous other objects in view as will appear as the description proceeds, the invention resides in certain novel features of construction, and in the combination and arrangement of parts as will be 20 hereinafter more fully described and claimed.

In the drawing:

Figure 1 is an elevation of the portable confessional showing the same on the back of the chair,

25 Figure 2 is a fragmentary detail section therethrough showing the clamp structure,

Figure 3 is an elevation of the clamp structure opposite to that shown in Figure 1.

Referring to the drawing in detail it will 30 be seen that the numeral 5 denotes a support such as a back of a chair. The numeral 6 denotes the central screen means and the numeral 7 denote two side screens which are hingedly engaged as at 8 on the sides of the 35 central screen 6, so that they may be folded over the central screen in a compact manner or may be extended outwardly therefrom somewhat at an oblique angle thereto.

40 A double clamp structure is indicated generally by the letter C and includes a plate 9 having a right angle extension 10 at one end, a right angle extension at the other end merging into a U-shaped portion 12 for receiving the lower edge of the screen 6 so that it may 45 be clamped therein by means of a clamp screw 14.

50 A plate 15 is welded or formed integrally with the extension 10 and depends therefrom so that the plate 9 is on one side of the back of the chair while the plate 15 is on the other

side thereof and the clamp screw 16 is engaged with the chair through the plate 15.

Thus the portable confessional may be mounted on the chair or any other suitable support.

55 From the above detailed description it will be seen that I have devised a simple and efficient portable confessional that may be manufactured at a low cost and yet remain strong and durable.

60 The present embodiment of the invention, however, has been disclosed in detail merely for the purposes of exemplification since in actual practice it attains the features of advantage enumerated as desirable in the statement of the invention and the above description.

65 It will be apparent that changes in the details of construction, and in the combination and arrangement of parts may be resorted to 70 without departing from the spirit or scope of the invention as hereinafter claimed or sacrificing any of its advantages.

Having thus described my invention, what I claim as new is:

75 A foldable, portable confessional for use on a chair or pew back, comprising a main screen composed of an open rectangular frame and reticulated material carried thereby, side screens hinged to and adjustable 80 swingably on the main screen and each composed of an open frame and reticulated material carried thereby, and means carried at the lower end of the vertical central portion of the main screen for detachably fixing the 85 same on a chair or pew back.

In testimony whereof I affix my signature.

JOHN M. LYONS.
